UNITED STATES PATENT OFFICE.

MARCUS T. HITCHCOCK, OF SPRINGFIELD, MASSACHUSETTS.

IMPROVEMENT IN CAR-VENTILATORS.

Specification forming part of Letters Patent No. 145,871, dated December 23, 1873; application filed June 4, 1873.

To all whom it may concern:

Be it known that I, MARCUS T. HITCHCOCK, of Springfield, in the county of Hampden and in the State of Massachusetts, have invented certain new and useful Improvements in Car-Ventilator; and do hereby declare that the following is a full, clear, and exact description thereof, reference being had to the accompanying drawings and to the letters of reference marked thereon, making a part of this specification.

The nature of my invention consists in a car-ventilator the rectangular frame of which is cast in one piece, with openings at the top for the upper journals of the dampers to enter, and with depressions at the bottom, into which the lower journals lie and are covered by protecting-plates, the dampers being cast with journals, and one of them having the crank for operating it cast therewith, all as more fully hereinafter set forth.

In order to enable others skilled in the art to which my invention appertains to make and use the same, I will now proceed to describe its construction and operation, referring to the annexed drawing, in which—

Figure 1 is a perspective view of my ventilating car-register, and Fig. 2 shows a part of the damper-frame. Fig. 3 represents the construction of the ventilator with but one damper.

A represents the damper-frame, which is made of cast-iron, with the holes *a a* in the upper end for the damper-pivots, all made by means of core-prints on the pattern, with iron cores to lie in the prints in the sand. These cores should be made tapering as far as they go into the casting, which will allow them to come out readily. The lower end of the frame A has impressions *b* made in the frame for the

lower damper-pivots, and two small caps, B B, which are riveted to the frame to hold the dampers in place. On the frame A is cast another cap, C, which covers the crank-damper, and forms a part of the ornamental part of the register. It will be noticed that the whole labor is performed by casting, with the exception of riveting the caps B B to hold the damper. D represents the center or crank damper, cast with the crank E in one piece, the crank being turned to one side, so as to stand with the angle desired, whether open or closed. D' D' are side dampers, cast with a pivot at each end, while the center damper D has a pivot at the upper end only, and the crank at the lower end. Each of the dampers has a projection, *d*, at its upper end for the reception of the rivets *x x* on the connecting-rod G, said rod and rivets being made in one piece.

Where only one damper is required, no side dampers or connecting-rod are used, and the frame is made only large enough to contain the center or crank damper.

Having thus fully described my invention, what I claim as new, and desire to secure by Letters Patent, is—

The combination of the frame A, with tapering sockets *a a* in its top bar, recesses *b b* in its bottom bar, the dampers D' D D', with journals on each end, and the plates B B, riveted to the frame A, all substantially as herein set forth.

In testimony that I claim the foregoing I have hereunto set my hand this 13th day of May, 1873.

M. T. HITCHCOCK.
